INVENTOR:

FLORENCE L. GRANT,

BY Albert, Davis

HER ATTORNEY.

UNITED STATES PATENT OFFICE.

FLORENCE L. GRANT, OF CLEVELAND, OHIO, ASSIGNOR TO GENERAL ELECTRIC COMPANY, A CORPORATION OF NEW YORK.

DESIGN FOR A LAMP SHADE OR REFLECTOR.

48,107.

Specification for Design.

Patented Nov. 9, 1915.

Application filed May 10, 1915. Serial No. 27,274. Term of patent 14 years.

To all whom it may concern:

Be it known that I, FLORENCE L. GRANT, a citizen of the United States, residing at Cleveland, in the county of Cuyahoga and State of Ohio, have invented a new, original, and ornamental Design for Lamp Shades or Reflectors, of which the following is a specification, reference being had to the accompanying drawing, forming part thereof.

In the drawing, Figure 1 is a plan, and Fig. 2 is an elevation of a reflector embodying my invention.

I claim—

The ornamental design for a lamp shade or reflector as shown.

In witness whereof, I have hereunto set my hand this 5th day of May, 1915.

FLORENCE L. GRANT.
